[57] CLAIM

The ornamental design for hand controller, as shown and described.

DESCRIPTION

FIG. 1 is a top plan view of a hand controller;
FIG. 2 is a left side elevation, the right side being a mirror image;

FIG. 3 is a bottom plan view;
FIG. 4 is a front elevation; and,
FIG. 5 is a rear elevation.

The broken line drawing of a keypad in FIGS. 1, 2, 4, and 5 is for illustrative purposes only and forms no part of the claimed design.
